[57] CLAIM

The ornamental design for ovenable food tray, as shown and
described.

DESCRIPTION

FIG. 1 is a top perspective view of an ovenable food tray
showing our new design;

FIG. 2 is a top plan view thereof;

FIG. 3 is a bottom plan view thereof;

FIG. 4 is a front elevation thereof;

FIG. 5 is a rear elevation thereof;

FIG. 6 is a right side elevation thereof; and,

FIG. 7 is a left side elevation thereof.

In the preferred, illustrated embodiment, the 45 degree shade
lines indicate a reflective surface.
